WRIST WATCH ATTACHMENT

Wallace Greene, Brooklyn, N. Y.

Application November 1, 1949, Serial No. 124,908

5 Claims. (Cl. 224—4)

1

This invention relates to an attachment for wrist watches and more particularly for combination with the spring lug pins in the ears of wrist watches.

It is an object of my invention to provide an attachment forming a belt clamp or the like for combination with the spring lug pins supported between ears of a wrist watch holding a wrist watch attached on the belt and to be clamped thereon instead of wearing on the wrist, the attachment including spring means normally urging the wrist watch supported upon a bracket of the clamp and permitting tilting of the watch when worn on the belt for ready inspection thereof, and alternatively including prop means combining with the clamp whereby the wrist watch may be braced in upright tilted position on a night table or the like, to form a stand for the wrist watch.

Still more particularly it is an object of my invention to provide an attachment forming a belt engaging clamp supporting a wrist watch for combination with the spring lug pins held between ears thereof and including a body of sheet material spaced into spaced branches joined resiliently by a loop to form a belt engaging clamp. In said device the branches comprise a front face clamp arm and a rear face clamp arm, a portion of said front face arm being shaped to form a tubular or ring-shaped bracket normally to sleeve over the spring lug trunnioned between the ears of the wrist watch. The clamp coordinately forms a base for the wrist watch, cooperating with a prop member pivotally supported on the opposed spring lug to brace the watch in a tilted position on a surface.

To attain these objects and such further objects as may appear herein, or be hereinafter pointed out, I make reference to the accompanying drawing forming a part hereof, in which:

Figure 1 is a perspective view showing my device with a fragmentary portion of the belt to which it is attached;

Figure 2 is a perspective view showing the watch tilted for inspection;

Figure 3 is a section taken on the line 3—3 of Figure 1;

Figure 4 is a magnified section taken on the line 4—4 of Figure 3;

Figure 5 is a section taken on the line 5—5 of Figure 4;

Figure 6 is a side elevation of the watch and attachment used as a travelling watch;

Figure 7 is a rear view taken in the direction of the lines 7—7 of Figure 6.

2

Summarizing my invention, it has as its object to provide a belt clamp having a bracket which may fit between the spring lug ears of a wrist watch to serve as the pivot about the spring lug pin normally used in the wrist watch and which serves as a pintle to convert the wrist watch from one worn on the wrist upon removal of the bracket bands to one which may be worn on the belt and in this position permitting tilting of the watch from a normally spring biased position against the body or belt to facilitate reading of the watch. Coordinately, the belt clamp attachment contemplated by me forms a base for the wrist watch, cooperating with a prop member attachable to the opposed spring lugs whereby a travelling watch supportable on a night stand or the like is secured.

Making reference to the drawing, I show a fragment of a waistband or garment belt 10 which may be used to support the wrist watch attachment 11 and which comprises a strip of sheet metal bent to provide spaced branches 12 and 13, joined by the loop 14 which normally biases the branches 12 and 13 toward each other. The rear face clamp arm 12 is die-drawn to form spaced arms 15 and 16, joined by the cross branch 17 and providing an abutting edge 18 and flared side edges 19 and 20, converging from the abutting edge for purposes which will appear as this description proceeds.

The front face clamp arm 11 is generally ring shaped, having an aperture 21 through which the rear face clamp arm 12 is accessible. A cross arm 22 is formed adjacent the loop 14, supporting a bracket 23 of generally tubular contour, whose edges 24 may fit between the ears 25 of the wrist watch 26. The ears 25 normally employ trunnion the spring lug pin 27. The bracket 23 retains the helical spring 28, having one end 29 anchored in a slot 30. The opposite end 31 of the spring extends through a slot 32 to bear upon the edge 33 of the watch.

With the arrangement provided, the watch 26 is biased by the spring 28 to lie in contact with the front face clamp arm 13. The watch is mounted in inverted position upon the belt 10, as shown more clearly in Figures 1 and 2 and when so worn, may be read merely by tilting the watch horizontally, as shown in Figure 2, for inspection.

When not in use the attachment includes a prop arm 34, having a sleeve 35 at one end, which may fit between the ears 36 of the wrist watch sleeved over the spring lug pin normally employed in this position to connect the bands of

a wrist watch strap. As in the prior embodiment, a spring 37 is retained within the sleeve 35 and has its opposite ends sprung to move the prop member 34 normally toward the back 38 of the watch. The prop member 34 is formed with a leg portion 39 having a shoulder 40 which may fit between the branches 19 and 20 of the rear face clamp arm 12. When not in use as a wrist watch clamp support on the belt 10, the clamp may rest upon the surface S, as shown in Figure 6.

Tilting the watch for reading as a travelling clock or night watch may be effected by pivoting the brace arm 34 against the resilient tension of the spring 37 until the leg portion 39 abuts the edge 18 and the shoulder portions 40 contact the inner face of the rear face clamp arm 12. The tapered edges 19 and 20 restrain the prop arm 34 from moving to the collapsed position shown in Figure 2, bracing the wrist watch face in a partially erect position.

It will thus be observed that I have provided an attachment for ready combination with the spring lug pin and ears of a wrist watch, and upon removal of the usual wrist watch bands, I may convert the watch to one which may be worn on the belt or in a similar attaching position. When worn as shown in Figures 1, 2 and 3, the watch is held against displacement by the clamping action of the rear face clamp arm 12 and the front face clamp arm 13.

Additionally, where the portion 39 engages the belt held between the arms 12 and 13, accidental displacement of the watch from the belt is minimized.

It will also be understood that while I show the prop arm 34 in a position normally tending to bias the prop arm outwardly, a reverse biasing action is feasible provided the spring 37 is less intense than the spring action between the arms 12 and 13, thereby cooperating with the clamp arm frictionally to engage the belt 10 and further minimizing accidental displacement.

Having thus described my invention and illustrated its use, what I claim as new and desire to secure by Letters Patent, is:

1. An attachment forming a belt clamp or the like for combination with the spring lugs of a wrist watch comprising a strip having branches joined by a loop to form a front face clamp arm and a rear face clamp arm, the front face clamp arm having a bracket adjacent said loop to lie adjacent the spring lug ears of the wrist watch and sleeved over the spring lug pin normally trunnioned between the ears, and spring means biased against said clamp arm.

2. An attachment forming a belt clamp with the spring lug ears of a wrist watch comprising a body of sheet material shaped into spaced branches joined by a connecting loop resiliently to spring bias said branches toward each other, and providing a front face clamp arm and a rear face clamp arm, a bracket extended from said front face clamp arm adjacent said loop, said bracket being tubularly shaped to lie between the spring lug ears of the wrist watch and sleeved over the spring lug pin normally trunnioned between the ears.

5. An attachment forming a belt clamp or the like for combination with one pair of the spring lug ears of a wrist watch comprising a strip having spaced branches joined by a connecting loop resiliently and forming a front face clamp arm and a rear face clamp arm, normally lying in contact with each other, the front face clamp arm being ring shaped to make the rear face clamp arm accessible therethrough, and bracket means adjacent said loop to lie between the spring lug ears of the wrist watch and sleeved over the spring lug pin normally trunnioned between the ears, and spring means for said pin to bias the watch against the front face clamp arm.
10. 4. An attachment forming a belt clamp or the like for combination with one pair of the spring lug ears of a wrist watch comprising a strip having spaced branches joined by a connecting loop resiliently and forming a front face clamp arm and a rear face clamp arm, normally lying in contact with each other, the front face clamp arm being ring shaped to make the rear face clamp arm accessible therethrough, and bracket means adjacent said loop to lie between the
20. 5. An attachment forming a belt clamp or the like for combination with one pair of the spring lug ears of a wrist watch comprising a strip having spaced branches joined by a connecting loop resiliently and forming a front face clamp arm and a rear face clamp arm, normally lying in contact with each other, the front face clamp arm being ring shaped to make the rear face clamp arm accessible therethrough, and bracket means adjacent said loop to lie between the
25. 6. An attachment forming a belt clamp or the like for combination with one pair of the spring lug ears of a wrist watch comprising a strip having spaced branches joined by a connecting loop resiliently and forming a front face clamp arm and a rear face clamp arm, normally lying in contact with each other, the front face clamp arm being ring shaped to make the rear face clamp arm accessible therethrough, and bracket means adjacent said loop to lie between the
30. 7. An attachment forming a belt clamp or the like for combination with one pair of the spring lug ears including a leg portion engaging one of said clamp arms and forming therewith a base for the wrist watch to support the watch angularly upright.

35. 8. An attachment forming a belt clamp or the like for combination with one pair of the spring lug ears of a wrist watch comprising a body of sheet material shaped into spaced branches joined by a resilient loop to spring-bias said branches toward each other, providing a front face clamp arm and a rear face clamp arm, each of said clamp arms being generally ring shaped, the front face clamp arm having bracket means and spring means normally to bias the watch in engagement with the front face clamp arm, and prop means having pivotal means for engagement with the spring lug pin normally carried by the opposed ears of the wrist watch, said prop means having locking means for engagement with the clamp arms to brace the wrist watch in an angularly erect position.

WALLACE GREENE.
